Primary Examiner — Ricky Pham**CLAIM**

The ornamental design for silicone sleeve bamboo lid, substantially as shown and described.

DESCRIPTION

FIG. 1 is a front perspective view of silicone sleeve bamboo lid, showing my new design;

FIG. 2 is a rear perspective view thereof;

FIG. 3 is its separate state diagram;

FIG. 4 is its use state diagram;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a front perspective view of a second embodiment thereof;

FIG. 12 is a rear perspective view thereof;

FIG. 13 is its separate state diagram;

FIG. 14 is its use state diagram;

FIG. 15 is a front view thereof;

FIG. 16 is a rear view thereof;

FIG. 17 is a left side view thereof;

FIG. 18 is a right side view thereof;

FIG. 19 is a top view thereof; and,

FIG. 20 is a bottom view thereof.

The broken lines in the drawings illustrate the portions of silicone sleeve bamboo lid, which form no part of the claimed design.
